HOUSING FOR A POWER HAND DRILL Piero Puddu, Milan, Italy, assignor to
Berettafiochi S.p.A., Milan, Italy

Filed Apr. 8, 1969, Ser. No. 16,627

Claims priority, application Italy Oct. 11, 1968

Term of patent 14 years

Int. Cl. D8—02

U.S. Cl. D8—68

Fig. 1.

Fig. 2.

Fig. 3.

FIG. 1 is a side view of a housing for a power hand drill showing my new design;

FIG. 2 is a side view opposite that shown in FIG. 1;

FIG. 3 is a rear perspective view thereof.

The right hand end of the housing, as referred to in FIG. 1, is flat when seen in end view, and, as seen from FIG. 3, is defined by a rectilinear upper edge.

I claim:

The ornamental design for a housing for a power hand drill, as shown and described.
